UNITED STATES PATENT OFFICE.

VALENTINE J. MOHLER, OF BALTIMORE, MARYLAND, ASSIGNOR TO LIQUID CARBONIC COMPANY, A CORPORATION OF ILLINOIS.

CROWNING MACHINE.

Application filed February 23, 1922. Serial No. 538,537.

To all whom it may concern:

Be it known that I, VALENTINE J. MOHLER, a citizen of the United States, residing at Baltimore, in the county of Baltimore and 5 State of Maryland, have invented certain new and useful Improvements in Crowning Machines, of which the following is a specification.

The machine to which my invention relates has for its purpose the application to bottles of caps or crowns for sealing the same. The bottles for sealing which my improved machine is used are formed around the mouth thereof with a small bead and the 10 cap or crown for sealing the bottle consists of a flat circular portion with a short flange or skirt made of fairly stiff sheet metal and provided with a lining washer for effecting an air tight joint with the mouth of the bottle. The flange or skirt of the cap is crimped or corrugated longitudinally and outwardly flaring for application to the bottle so as to 15 permit the bead upon the latter to enter the flange and form a close joint with the washer in the cap. After the cap is applied to the mouth of the bottle the crimped flange is forced inward so that the inner ridges of the corrugations extend under the bead on the mouth of the bottle and thereby lock the cap 20 to the bottle.

The locking of the cap to the bottle requires considerable pressure and is accomplished by means of machinery, a number of machines having been devised for this purpose. One form of such machine is shown 25 in Patent 473,776 granted to William Painter April 26, 1892. In this machine, after the cap has been applied to the bottle, it is thrust upwardly into a tapering annular die by which the corrugated flange is forced inward into locking position. In another well known form of bottle capping machine an 30 annular series of pivoted radially movable fingers is provided which receive the cap and when the latter is in position upon the mouth of the bottle the fingers are driven inwardly against the lower corrugated edge of the cap flange to force it under the bead upon the bottle mouth.

Difficulties have been encountered with 35 bottle capping machines prior to my invention due to the slightest variations in the length or height of bottles of the same commercial size due to slight irregularities in the process of manufacture thereof. In the

machines of the prior art it is necessary that the mouth of the bottle in the crimping position occupy an exact longitudinal relation to the crimping means. If the bottle happens to be a little longer than the average, 60 unless special provision is made for such irregularities, it is crushed when the bottle seat and the capping head come to the sealing position or the cap sticks in the sealing head, in either event requiring either the 65 stopping of the machine or at least the intervention of the operator. Efforts have been made to overcome the difficulty by providing springs intermediate the capping head or the bottle seat and its support but this has not 70 proved entirely successful as the springs must be made strong in order to properly effect the locking of the crowns that they frequently break the bottles.

It is the object of the present invention to 75 provide a capping or crowning head which will satisfactorily apply crowns or caps irrespective of irregularities and variations in the height of bottles without risk of breaking the same and which is simple and 80 efficient requiring but little attention upon the part of the operator. My present invention relates to the crowning head per se and may be used in connection with any of the well known forms of bottle capping machines 85 irrespective of their other features provided only that they are adapted to present the bottles to be capped with the caps applied thereto to the crowning heads and move the bottles and the respective crowning heads axially into sealing position. In the accompanying drawing forming part of this application I have shown a preferred form of the invention as applied to a rotary bottle capping machine, having a number of crowning heads which are vertically movable into 90 their operative relation with bottles resting upon seats provided beneath the respective heads; it is to be understood, however, that the specific disclosure is for the purpose of 95 exemplification only and the scope of the invention is defined in the following claims in which I have endeavored to distinguish it from the prior art so far as known to me without, however, relinquishing or abandoning any portion or feature thereof.

In the drawing Fig. 1 represents in side elevation partly in section a bottle capping machine of the rotary multiple type to which my invention has been applied, Fig. 2, 100

a vertical axial section partly in elevation and on an enlarged scale of a preferred form of my invention, Fig. 3, a horizontal section on the line 3—3 of Fig. 2 and Fig. 4 5 is a perspective of a detail.

Referring to Fig. 1 in which I have illustrated my invention as applied to a machine of the rotary type it will be seen that the machine comprises a stationary 10 framework 5 in which is revolvably mounted and driven, a shaft 6 which carries two or more crowning heads 7 and a bottle carrier 8 having seats 9 in registry with the respective crowning heads. The shaft may be 15 driven in any obvious manner and is provided with a sleeve 10 bolted thereto and having cross-heads 11, 12 having guide openings in which the respective crowning heads reciprocate toward and from the 20 bottle seats. Reciprocation of the crowning heads is effected by means of a cam guide 13 upon a stationary sleeve 14, the upper ends of the crowning heads being provided with rollers 15 running in said cam guide. 25 The sleeve 14 is bolted to an upper frame member 16. Said upper frame member and a lower frame member 17 are connected together by an intermediate housing wall 18 and are formed with bosses 19, 20 respectively, sliding upon two vertical rods 21 (of which only one is shown in the drawing). The rods 21 are mounted in bosses 22, 23 on the upright 24. The frame or housing including the members 16, 17, 18 is 30 adjustable upon the rods 21 to accommodate bottles of different sizes, the adjustment being effected by means of a rack 25 on the housing and a pinion 26. When adjusted the housing is locked to the rods by 35 an ordinary cramping device 27 in boss 20. It will be understood that in order to permit this adjustment the rotary shaft 6 is keyed to the pinion by which it is driven so that it is raised and lowered with the 40 housing when the latter is adjusted as above described. I have shown the machine as provided with a hopper 27' for feeding crowns to the bottles which may be of any suitable form or be dispensed with altogether as the crowns may be fed to the 45 bottles by hand or otherwise.

It will be understood that as the shaft revolves, carrying with it the table support and crowning heads the latter reciprocate, 50 a bottle being fed under each crowning head and a crown applied thereto as the head is in the raised position shown at the left of Fig. 1 and the head then descends and secures the cap or crown in a manner 55 to be now described.

The essence of the present invention consists in providing a circular die into or 60 through which the mouth of the bottle with the crown applied thereto is forced during the sealing operation, thus pressing the

crimped or corrugated flange of the cap against and under the bead on the mouth of the bottle, which die after the sealing operation has been completed, readily yields or spreads to permit the withdrawal of the 70 capped bottle. For this purpose the die is formed of a number of sections separated from each other on radial planes and means is provided whereby the sections are held in an inner position to constitute in effect 75 a rigid circular die during the sealing operation and permitted to spread immediately thereafter.

In the preferred form of the invention 80 illustrated in Figs. 2, 3 and 4, it will be seen that the die is composed of a number of radially movable sections 28 each formed with a knuckle or bearing portion 29 by which it is so supported as to have a limited swinging movement in a plane 85 radial to the die. The lower limbs of the die forming sections are formed on their inner faces with projecting portions 30 which together constitute the constricted portions of the die which is of such diameter 90 when in the closed position shown in Fig. 2 as to permit the passage therethrough of the bottle head with the crown thereon when the flange of the latter is pressed into locking position. The lower end of each 95 section is chamfered at 31 so that the circular series of sections provide a flared guiding opening to the die passage.

The crowning head comprises a plunger member 32 the upper end of which carries 100 the antifriction roller to which reference has been made and the lower end of which is hollow, reduced and screw threaded at 33 for attachment to the sleeve 34.

The upper end of the latter is threaded 105 to receive the reduced end of the plunger and the lower end which is of somewhat larger diameter as at 35 is exteriorly threaded as at 36 to receive the die carrying head 37. The latter supports the pivoted 110 die sections being formed for this purpose with a rabbet 38, which is arcuate in cross-section to receive and fit the knuckles of the respective die sections. A bearing ring 39 having a similar rabbet rests upon a shoulder 40 of head 37 and completes the bearing 115 for the knuckles of the die section. Beneath the curved groove or rabbet 38 the opening in the die supporting head is flared at 41 to permit the die sections to swing outward to the dotted line position shown in Fig. 2. For convenience in assembling the die sections are pivotally mounted upon a split ring 42.

The upper ends 43 of the die sections extend into an annular recess 44 in the lower end of sleeve 34, the recess being of sufficient diameter to permit the necessary swinging movement of the sections referred to hereinafter.

The internal diameter of sleeve 34 is re- 130

- duced at 45 near the lower end thereof to form a bearing for the longitudinally movable locking sleeve 46, the lower end of which is tapered as at 47 and of such diameter as to extend between the bearing faces 48 of the upper ends of the die sections when the latter are swung to the die forming position shown in Fig. 2 and firmly lock the sections in such position. The downward movement of the locking sleeve is limited by the engagement of the shoulder 48' formed on the upper end thereof with shoulder 49 on the main sleeve 34. The locking sleeve is shifted by a plunger 50 fitting and extending through the bore thereof and formed or provided at its lower end with an enlarged head 51 for engaging the cap or crown upon the bottle to be sealed. The plunger is also provided or formed with a collar 52 which normally rests upon the upper end of the locking sleeve 46 being yieldably held in engagement therewith by a spring 53 intermediate said collar and the lower reduced end 33 of plunger 32. Oil channels 54 and oil openings 55 are provided for lubricating the bearing in which the knuckles of the die-forming sections are supported.
- The operation of the crowning head will now be apparent. A bottle being placed on the corresponding seat and provided with a sealing crown the rotation of the machine causes the crowning head to descend. The plunger 50 first comes in contact with the sealing crown on the bottle and as the head continues to descend retreats into the head under the pressure of the capped bottle. The locking sleeve 46 remains seated in the position shown in full lines in Fig. 2 thus maintaining the die in the closed or contracted full line position. The cap or crown is forced through or well into the die opening which wipes or presses the corrugated flange of the crown against and beneath the bead upon the mouth of the bottle. The further descent of the crowning head forces the bottle and the plunger 50 further into the throat until the upper end of head 51 engages the lower end of the locking sleeve 46 driving the latter upwardly from its seat until its lower end is sufficiently above the die sections to permit the upper ends of the latter to swing inwardly. This permits the members to swing to the dotted line position in Fig. 2 in which the cap and bottle are fully relieved and as the crowning head rises it readily leaves the bottle and crown. This completes the sealing action and the bottle is then ready to be removed from the machine. As the crowning head rises releasing the pressure of the bottle on the plunger 50 the latter returns to its lowermost position restoring the locking sleeve 46 to its seat.
- It will now be apparent that with my improved crowning head any usual or possible variations in the height of bottles due to irregularity of manufacture are immaterial, the taller bottle simply driving the crown a little further into or through the die opening than the shorter bottle. There can be no sticking or catching of the bottles in the crowning head because when the die sections are unlocked by the retreat of sleeve 46 they are free to swing outward to relieve any pressure upon the crown.
- As heretofore stated my improved crowning head is applicable to bottle capping machines generally for securing crown caps to bottles in which mechanism is provided for pressing the crowned bottle upwardly into the die of the crowning head.
- I claim—
1. In a device of the class described, a sectional die comprising a plurality of radially movable members, rigid means for locking said members inwardly in die-forming position and adapted to release the members to permit them to move outwardly and a spring for normally holding said means in locking position.
  2. In a device of the class described, a sectional die comprising a plurality of radially movable members, means for locking said members in their innermost position, said means movable axially of the die to permit said members to recede from their innermost position and a spring for normally holding said means in locking position.
  3. In a device of the class described, a sectional die comprising a plurality of independently radially movable members, a plunger movable axially of said die by engagement with a bottle to be crowned, and means movable into and out of operative position by said plunger for alternately rigidly locking said die members in die-forming position and releasing the same.
  4. In a device of the class described, a support, an annular series of die-forming members pivotally mounted in said support, means movable axially of the die for normally rigidly locking said members in die-forming position and a spring normally holding said means in locking position.
  5. In a device of the class described, a support, an annular series of die-forming members pivoted in said support for radial swinging into and out of die-forming position, a plunger adapted to engage and be operated by the cap of a bottle to be sealed, and means for rigidly locking the die-forming members in die-forming position operable by the movement of said plunger to release the members.
  6. In a device of the class described, a hollow support, an annular series of pivoted die-forming members mounted on said support, a plunger movable axially of said support and die adapted to be engaged and

- 5 moved by the cap of a bottle to be sealed, and a sleeve movable longitudinally of said plunger and of said support normally engaging and rigidly locking said die-forming members in die-forming position and operated by the plunger to release said die-forming members.
- 6 7. In a device of the class described, a support, an annular series of die-forming members 10 pivoted on said support and swinging in radial planes, said members having arms extending in opposite directions from their pivots, the arms of said members below their pivots forming when in inner position a die 15 and having a cylindrical surface, means movable axially of the die to engage the upper end of said die-forming members and lock them in die-forming position.
8. In a device of the class described, a support, an annular series of die-forming levers 20 pivoted on said support intermediate their ends and swinging in a radial plane, the lower ends of said levers being shaped and arranged when in their innermost position 25 to form a circular die, a sleeve engaging the upper ends of said levers to lock the latter in die-forming position, and a plunger on which said sleeve is mounted adapted and arranged to be engaged by the cap of a bottle 30 to be sealed and to be raised thereby, and means on the plunger to engage said sleeve when raised and move the sleeve out of lever 35 engaging position.
9. In a machine for crowning bottles, a sectional die composed of radially movable sections, means normally locking the section in inner die-forming position, means movable axially of the die by contact with a bottle for shifting the locking means to unlock- 40 ing position.
10. In a bottle crowning machine, a die composed of radially movable sections, means normally locking the sections in their inner die-forming position, means for forcing a bottle with a crown thereon into the die 45 and means operated by the crowned bottle for shifting the locking means into unlocking position.
11. In a bottle capping machine, a die composed of pivoted radially movable sections, an annular support for said sections, a plunger extending through the die and adapted to engage a bottle to be capped and to be moved thereby and means normally locking the sections in inner, die-forming 50 position adapted to be engaged by said plunger and shifted to unlocking position.
12. In a bottle crowning machine, a sectional die comprising a plurality of sections pivoted to swing in planes radial to said die, 60 a sleeve concentric with said die and movable axially thereof and adapted in one position to lock the sections to form a rigid die, a plunger movable axially through said sleeve and a shoulder on the plunger adapted 65 to engage the sleeve and move it out of locking position.
13. In a machine of the class described, a head, an annular series of die forming sections pivoted in said head and swinging in radial planes, an axially movable sleeve concentric with the die having a cylindrical surface adapted when the sleeve is in lowered position to engage the die sections and lock them in die-forming position, 70 and means adapted to be engaged by a bottle and to engage the lower end of said sleeve to move the latter into releasing position.

VALENTINE J. MOHLER.
